2,196,795

FIREPLACE HEATER ATTACHMENT

William T. Harris, Bellingham, Wash.

Application March 6, 1939, Serial No. 260,197

4 Claims. (Cl. 126—121)

My invention relates to attachments for fireplaces for heating the air of the room and augmenting the heat radiated by the usual fireplace.

5 An object of my invention is to provide a device of this type which is readily applied to and removed from a fireplace.

A further object is to provide such a device which will not injure the brick work of the fireplace and/or chimney by the expansion and contraction thereof in use.

10 A further object is to provide a novel combined air heater and damper for a fireplace.

15 A further object is to provide an air heater for a fireplace providing a rearwardly located smoke passage, a downwardly and rearwardly sloping surface on said heater, and a damper slideable by gravity on said surface and normally closing said smoke passage.

20 Other objects and advantages reside in the particular structure of the device, combination and arrangement of the several parts thereof, and in the particular manner of operation, all of which will be readily apparent to those skilled 25 in the art upon reference to the drawing in connection with the following detailed description.

In the drawing:

Figure 1 is an elevation of the fireplace to which my device is attached;

30 Figure 2 is a side elevation thereof;

Figure 3 is a vertical section taken on a plane corresponding to line 3—3 of Figure 5;

Figure 4 is a vertical section taken on a plane corresponding to the line 4—4 of Figure 5;

35 Figure 5 is a horizontal section taken on the line 5—5 of Figure 1;

Figure 6 is a horizontal section taken on the line 6—6 of Figure 3;

Figure 7 is a vertical section taken on the line

40 7—7 of Figure 4;

Figure 8 is a vertical section illustrating a modification.

In the drawing, wherein like reference characters have been used throughout to designate 45 like parts, 10 designates generally a conventional fireplace, 20 indicates a heating chamber, 11 indicates a damper slideable thereon to close a smoke passage 25, and 12 indicates any suitable actuating means for the damper. While I have 50 shown a particular form of fireplace, it is obvious that this is merely a conventional form and can be replaced by any other well known structure. The reference characters 13 and 14 represent respectively outlet and inlet grills covering 55 the outlet and inlet passages for the air to be

heated by the fireplace. The inlet grills 14 are located in upright hollow members 15 located on either or both sides of the fireplace 10. The members 15 may be formed integral with the fireplace structure as shown or they may be separate elements which are attached thereto after the fireplace has been built. The upper ends of the members 15 are formed to provide inwardly directed openings 16 which discharge cold air through opening 21 in a heating chamber 20 in 10 the fireplace. The heating chamber 20 is removably supported in the fireplace upon frame members 18 which are attached to the fire-bricks 19 of the fireplace 10. The heating chamber 15 20 may be loosely supported upon the frame 18 to facilitate the ready removal of the chamber from the fireplace or, the heating chamber may be attached to the frame work in any suitable manner (not shown).

The heating chamber 20 comprises a rectangular box-like structure shaped like a parallelogram in side elevation. However, it is obvious that the shape of the heating chamber will vary in accordance with the shape of the fireplace to which it is applied. However, it is believed to 25 be important that the lower surface thereof slope upwardly toward the rear of the fireplace, as shown, to facilitate the free flow of the products of combustion rearwardly and upwardly around the heating chamber to the chimney as indicated 30 by arrows in Figure 5. The top of the heating chamber 20 is formed to provide openings 22 therethrough at the inner end thereof.

Suitable reinforcing angle irons 17 in the heating chamber reinforce the same to prevent the 35 steel body thereof from being warped out of shape by the heat of the fire. If desired, the conduits 23 may be similarly reinforced by angle irons 24.

The top of the heating chamber 20 mounts at 40 least one upwardly slanting conduit 23 which connects one of the openings 22 of the chamber 20 with one of the outlet openings 13.

As shown in the drawing two inlet openings 14, conduits 15, openings 16, 21, 22, conduits 23 45 and outlet openings 13 are provided. However, one of each or more than two may be used if desired.

The damper 11 is slidably mounted on top of the conduits 23 and is actuated by gravity to 50 close the smoke passage 25 of the fireplace. The flexible means 12 of the damper permits it to be retracted to open the smoke passage.

It is to be noted that the heating chamber 20 and its appurtenances do not have to be tight- 55

ly fitted into the fire-place but may rest loosely on the support 18. This permits ready expansion of the heating chamber without damage to itself or to the fireplace lining.

5 It is to be noted also that the passage of air through the heater is ever in an upward direction throughout and that in each of the conduits 15, chamber 20 and conduits 23, the flow of air is free and unobstructed and in a straight line and it is not obstructed by baffles or other flow retarding means.

10 Figure 8 illustrates a modification wherein the parts 15 and 20 are identical to the preferred form but in which a conduit 27 has been substituted for the conduit 23 and leads to an up-stairs room instead of to the room in which the fireplace is located. This structure permits the same uninterrupted upward flow of the air and as the conduit 27 is in contact with the products 15 of combustion throughout its extent, there is no cooling of the air after it leaves chamber 20

20 In both forms of the invention the heating chamber 20 if formed of sheet steel or other suitable metal formed into a one piece structure. 25 The outlet conduits 23 are similarly formed and are preferably made integral with the chamber 20. However, they may be detachably connected thereto if desired.

25 While I have shown and described what is now thought to be a preferred embodiment of my invention, it is understood that the drawing and foregoing description is illustrative only except as hereinafter claimed.

I claim:

30 1. An air heater for a fireplace, comprising a quadrilateral heating chamber having parallel top and bottom walls, means mounting said chamber in the upper forward part of a fireplace with said bottom sloping upwardly toward the 35 rear of said fireplace and terminating short thereof to provide a smoke passage therebetween, at least one air inlet opening in said chamber adjacent the lowest point thereof, at least one air outlet opening at the highest point thereof, 40 at least one forwardly and upwardly sloping conduit leading from said outlet opening to a point outwardly of said fireplace, a damper slid- 45

able on the upper surface of said conduit and normally closing said smoke passage, and means outwardly of said fireplace for retracting said damper to open said smoke passage.

2. An air heater for a fireplace, comprising a 5 heating chamber, means mounting said chamber in a fireplace, air inlet and outlet means for said chamber, said chamber providing a smoke passage in said fireplace rearwardly of said chamber, said chamber providing a downwardly 10 sloping upper surface, and a damper slidable on said surface and adapted to close said smoke passage.

3. An air heater for fireplaces comprising, a 15 casing providing a heating chamber having separate air inlet and outlet openings, the inlet openings being disposed in a plane below that of the outlet openings and the latter discharging into the room, a fireplace wall-carried supporting frame for said casing and upon which the latter is freely supported, said supporting frame slanting upwardly and rearwardly from the front wall of the fireplace whereby to dispose said casing against said front wall with the casing bottom slanting upwardly and rearwardly therefrom to deflect the products of combustion rearwardly, and conduit means supplying air to said inlets from a point adjacent the floor.

20 4. An air heater for fireplaces comprising, a 25 casing providing a heating chamber having separate air inlet and outlet openings, the inlet openings being disposed in a plane below that of the outlet openings and the latter discharging into the room, a fireplace wall-carried supporting frame slanting upwardly and rearwardly from 30 the front wall of the fireplace and upon which frame said casing is freely supported with its bottom slanting upwardly and rearwardly to deflect products of combustion toward the rear of the fireplace, the width of said casing approximating the width of the fireplace and the air inlet openings being in the ends of said casing, and air supply conduits having outlets 35 registering with said casing inlet openings when the casing is disposed against the fireplace front 40 wall as aforementioned.

45 WILLIAM T. HARRIS.
